2,658,631

APPARATUS FOR FEEDING CLEATS TO
BOXMAKING MACHINES

David G. Kingsley, Mountain Lakes, N. J., assignor to Stapling Machines Co., Rockaway, N. J., a corporation of Delaware

Application March 31, 1951, Serial No. 218,643

9 Claims. (Cl. 214—8.5)

1

This invention relates to apparatus for dispensing cleats to a box-making machine, the apparatus being particularly adapted for dispensing cleats of two different lengths into their proper respective positions upon the conveyors of the box-making machine.

The apparatus of the present invention is especially useful with box-making machines of the general class disclosed in United States Patent No. 2,304,510, issued December 8, 1942. In such machines, continuously moving conveyor bands carry properly arranged box parts past a transverse row of stapling units by which the box parts are stapled together to form box part units or complete wirebound box blanks.

The box units are usually formed of side material such as slats, and supporting cleats stapled thereto. A wirebound box includes a plurality—usually four—of such box units or "sides" foldably secured together by binding wires stapled to each of the sides so that when the sides are folded to form the box, the binding wires extend around the box and the two ends of each of the binding wires may be fastened together to close the box. The cleats usually have mitered or notched ends so that the adjacent ends of the cleats will abut or interfit snugly when the sides of the box are folded.

In making box blanks, the cleats are usually placed first on the conveying mechanism of the box-making machine, and the side material is then laid on top of the cleats. Both the cleats and side material are engaged by spaced pushing elements on the conveyor bands of the machine, and thus conveyed in properly arranged relation to the stapling mechanism.

Until recently, the placement of the slats and cleats has been accomplished almost exclusively by manual labor. In the copending application, Serial Number 70,868, and issued on June 3, 1952, as U. S. Letters Patent No. 2,599,460, there is disclosed apparatus for mechanically dispensing cleats to a box-making machine. This apparatus, however, is primarily adapted for dispensing cleats of only one length and is not well adapted for applications where cleats of more than one length must be dispensed. Where all of the sides of a box have equal dimensions—for example, as in boxes with square ends—the dispensing apparatus need be capable of handling cleats of only one length. Where, however, the ends of the boxes being made are oblong, so that the width and depth of a box are unequal, the apparatus must be capable of dispensing alternate cleats of different lengths.

2

The present invention provides apparatus for mechanically dispensing cleats of at least two different lengths into their proper respective positions on the conveying mechanism of a box-making machine. As will be described more particularly hereinafter, means is provided to prevent the longer cleats from tipping downwardly where they will be engaged by the pushing elements provided for engagement with the short cleats, as would otherwise tend to occur, with possible jamming of the dispensing apparatus. Means is also provided to oscillate the cleats within the dispensing apparatus to prevent their becoming interlocked and impairing the proper dispensation of cleats.

Suitable illustrative embodiments of the invention are shown in the accompanying drawings, in which:

Figure 1 is a view of the right-hand side of a wirebound box-making machine showing an automatic cleat-dispensing apparatus embodying features of the invention installed adjacent the input or left-hand end of the machine as viewed in the figure;

Figure 2 is an enlarged fragmentary view of the left-hand half of the cleat-dispensing apparatus shown in Figure 1;

Figure 3 is a fragmentary end view of the dispensing apparatus, as viewed from the left-hand side of Figure 2;

Figures 4, 5 and 6 are enlarged fragmentary views of the portion of the dispensing apparatus appearing in the lower portion of Figure 2, with some parts omitted for clarity, and showing progressive steps in the dispensation of cleats of two different lengths;

Figure 7 is a view similar to Figures 4, 5 and 6, illustrating an alternative embodiment of the invention;

Figure 8 is a fragmentary end view of the dispensing apparatus shown in Figure 7, as viewed from the left-hand side of Figure 7;

Figure 9 is a view similar to Figure 2, but illustrating an alternative embodiment of the invention including means for facilitating the separation of interlocked cleats; and

Figure 10 is an end view of the apparatus shown in Figure 9, as viewed from the left-hand side of Figure 9 showing, in addition to the elements appearing in Figure 9, means for communicating power to the cleat-dispensing apparatus.

Figure 11 is a top plan view of the dispensing apparatus showing the hoppers in position over the conveyor bands of the box-making machine

and with the horizontal cleat guideways communicating with said hoppers.

In Figure 1, there is shown in somewhat diagrammatic elevation, the right-hand side of a box-making machine of the type disclosed in the aforementioned patent. Near the input or left-hand end of the machine in Figure 1, is shown a cleat-dispensing apparatus, generally designated A, embodying features of the present invention. The apparatus A is comprised of two sections B and C, having cleat hoppers D and E respectively, which supply cleats to the conveying mechanism at the left- and right-hand sides of the box-making machine. The conveying mechanism includes endless conveyor bands 2 trained about idler sprockets 3 at the front or input end of the machine and about driven sprockets 4 keyed to drive shaft 5 at the rear or output end. The box parts placed on the conveyor bands near the input end of the machine are conveyed under a transverse row of stapling units mounted between side frames 6 in the central portion of the machine, and the assembled box units or box blanks are removed from the conveyor bands at the output or right-hand end of the machine as shown in Figure 1.

Since, the construction of the dispensing apparatus A is similar in many respects to the cleat dispensing apparatus disclosed in the aforementioned application, Serial Number 70,868, the description of the present apparatus will be principally directed only to the features pertinent to the present invention. Also, since sections B and C of the apparatus are of generally similar construction, only section B, which supplies cleats to the conveyor band 2 at the left-hand side of the box-making machine, will be described in detail.

As may be seen in Figures 1 and 11, the side-walls of the apparatus are formed by plate members 8, and the apparatus is divided equally into sections B and C by a center wall or plate member 9. As shown in Figures 2 and 3, wall members 8 and 9 are supported and secured at the output or right-hand end of the apparatus A, by upstanding angle members 10 the lower ends of which are suitably secured to the longitudinal rail 31 which supports the conveyor band 2; the opposite ends of the wall members 8 and 9 are suitably supported by means not shown in the drawings. The members 8 and 9 are spaced apart a distance slightly greater than the length of the longest cleats to be dispensed, and secured by cross braces 11 (Figure 10). Horizontally positioned V-belts 12 running longitudinally between wall members 8 and 9 of sections B and C, are trained about idler V-pulleys (not shown) at the input end of the device A and have their oppositely disposed ends trained about V-pulleys 13 keyed to shaft 14, whose ends are journaled in bearings such as shown at 15 (Figures 3 and 9) fastened to the inner faces of wall members 8. The upper runs of the belts 12 are supported by longitudinal rails 16 (Figure 10) mounted on the cross braces 11. A plurality of bars or outer guide members 18 (see Figures 2, 3 and 11) are mounted in a common plane spaced above the upper runs of the belts 12 by a distance slightly exceeding the thickness of the cleats so as to form with the belts a horizontal channel or guideway through which the cleats may be moved by the moving belts. At the input end of the apparatus, these guide members 18 do not extend as far as do the belts, but are cut off short to leave a substantial length of the upper runs of

the belts exposed to facilitate manual placement of the cleats on the belts.

At the delivery end of the belts 12, the outer guide members 18 are curved concentrically to the curve of the belts around the pulleys 13, and extend vertically downward, their lower ends being supported by a horizontal cross brace 21 which is secured at its opposite ends to the side walls 8 and 9. A plurality of similar bars or inner guide members 17 are provided, having upper portions curved to follow the plane of the curved portions of the belts 12 and having lower portions extending vertically downward to rest upon a horizontally extending L-shaped cross brace 19 which is secured to the upstanding angle brackets 10.

The inner and outer guide members thus form a vertical trough or hopper D into which the cleats are fed by the moving belts. The cleats are stacked on the belts, with longer and shorter cleats alternating, and lying on their sides—that is, rotated about their long axes through an angle of 90° from the orientation in which it is desired ultimately to dispense them. The curvature of the guideway formed by the inner and outer guide members 17 and 18 and the belts results in rotation of the cleats through an angle of 90°, thereby achieving the desired orientation.

In order to provide access into the hopper D for rearranging or removing cleats, and so on, a gate is provided at the lower end of the hopper. This gate is formed of a plurality of vertical bars or guide members 25 secured to the inner face of a bracket 26 carried by a support member 27. This support member 27 is hinged at 28 to an L-shaped base 29 which in turn is secured to the angle rail 31 supporting the box parts conveying elements. When the gate is in closed position, as shown in Figure 3, the bars 25 are in the same plane and in axial alignment with the downwardly projecting portions of bars 18.

The gate is opened by rotating it clockwise about the hinge 28, as indicated by arrow 32 (Figure 3). Latches 33 (Figure 2) are provided to maintain the gate in normally closed position.

As may be seen in Figures 2 and 3, the hopper D is closed at its side adjacent the trailing end of the cleats—the left-hand side as viewed in Figure 2—by a fixed guide member 34 which extends downwardly from wall member 8 with its inner face in alignment with that of wall member 8. The lower end of the guide member 34 is shaped into an inclined shelf 36 which extends inwardly of hopper D to a predetermined point beneath the trailing ends of the longer cleats in approximately the third-from-bottom position in the stack of cleats in the hopper. The opposite end of hopper D, shown at the right in Figure 2, is closed by a movable guide member 37 hinged at 38 to a bracket 39 fastened to the outer surface of center wall member 9, and held in position by latch 96 pivoted about pin 97 on cross brace 21, engaging pin 98 in guide member 37. The inner surface of guide member 37 is in alignment with that of center wall member 9 to provide a guide for the leading ends of all cleats, both long and short. The bottom end of guide member 37 is notched out to receive the upper end of an exit gate 41 which is pivotally mounted on a pin 42 extending from guide member 37. The exit gate 41 extends downwardly a predetermined distance, and provides a recess or offset 43 to compensate for and cooperate with inclined shelf 36, by permitting slight forward

movement of a cleat in the second-from-bottom position in the stack. Exit gate 41 is normally held in closed position, as shown in Figure 2, against the stop 44 formed by the notch at the lower end of guide member 37, by a spring finger 45, the upper end of which is secured to the outer surface of guide member 37 and the lower free end of which bears against the outer surface of exit gate 41.

The source of driving power for the cleat-conveying elements of device A is shown in Figures 9 and 10, particularly in Figure 10. A motor 46 is coupled to the drive shaft 14 through a speed reducer 48, a sprocket 47, drive chain 49, and sprocket 50 keyed to shaft 14. There is thus imparted to the drive shaft 14 a clockwise rotation, as viewed in Figure 10, which drives the pulleys 13 and belts 12 so that the belts move at a speed slightly in excess of the rate at which cleats are removed from the hopper.

To describe more fully the operation of device A and particularly certain elements of this invention and their function in the process of feeding cleats of two different lengths, reference is made to Figures 2, 3, 4, 5, and 6.

At the commencement of operations, the feed belts 12 of sections B and C and their respective hoppers D and E are completely loaded with cleats of alternate lengths, with the bottom cleat in each of the hoppers being of the length corresponding to that of the space ahead of the first spacer element X or Y which will pass beneath the hopper when the conveyors 2 are started in movement. The cleats are placed in the hopper so that the leading end of each cleat is against the inner face of the adjacent wall member, as shown in the drawings.

With rotation imparted to shaft 14, the moving belts 12 continuously exert pressure upon the column of cleats stacked in hopper D by means of friction between the belts and the cleats thereon. With the egress of each successive cleat from the hopper, the column of cleats in the hopper is permitted to drop by a distance equal to the thickness of a cleat; and other cleats are moved forward by the belts to fill up the space vacated.

As may be seen in Figures 4, 5, and 6, a cleat support step 52, similar to that disclosed in the aforementioned application Serial No. 70,868, is provided at the bottom of the hopper, extending from the trailing end of the hopper to a point slightly forward of its center; the step thus affords support for the trailing end of the column of cleats in the hopper.

At the start of operation, a dummy cleat V may be placed upon cleat support track 53 with a portion of its trailing end supporting the column of cleats in hopper D, as shown in Figure 4.

With this initial arrangement, and with the conveyors 2 of the box-making machine moving in the direction indicated by arrow 51, dummy cleat V is moved by push finger X' of the leading spacer element X from its position shown in Figure 4 to that shown in Figure 5, thereby removing both the dummy cleat V and push finger X' from beneath the short cleat a, allowing the column of cleats in hopper D to drop, and placing short cleat a in the desired space S (Figure 4) between push finger X' of the leading spacer element X and push finger Y' of the next following spacer element Y when space S between push finger X' and push finger Y' attains a position as shown in Figure 5. In Figure 5, short cleat a is shown resting upon cleat support step 52 with

its leading end a' about to clear the bottom of exit gate 41. It will also be seen that the trailing end b² of the next long cleat b above is momentarily supported on inclined shelf 36, while the forward end b' of long cleat b has moved downward to the second from bottom position in the stack of cleats, in position to enter offset 43. With continued movement of short cleat a by push finger Y' frictional engagement between the upper surface of cleat a and bottom surface of cleat b causes long cleat b to follow in the same direction and enter offset 43, which allows the trailing end b² of long cleat b to drop from inclined shelf 36 to its position shown by dot-dash lines P in Figure 6. In this position, the trailing end b² of cleat b is supported on the step 52, and its leading end b¹ is tilted upward where it will engage exit gate 41. Continued movement of conveyors 2 will move push finger Y' from beneath forward end b¹ of long cleat b, allowing said long cleat to drop to a horizontal position upon cleat support step 52, as shown in dash lines in Figure 6. Long cleat b is then in position to be contacted by push finger Z and moved beneath exit gate 41 and out of the hopper. The sequence of operations just described follows as each short cleat a and long cleat b arrive at the bottom of hopper D.

While the procedure described above and shown in the figures indicates that short cleat a is the initial cleat fed from hoppers D and E, it will be understood that the reverse procedure may be followed equally as well, that is, long cleat b may be the initial cleat fed. The cleat arrangement is, of course, determined by the pattern of spacer elements on the conveyors 2.

The momentary engagement of the trailing end of each long cleat with the inclined shelf 36 until the leading end of the cleat can clear the lower end of the guide 37 and move into the notch 43, serves a very important purpose. If it were not for this arrangement, the trailing end b² of the long cleat b in Figure 4, for example, would tip downwardly into the path of the push finger Y' so that this push finger, which should engage the trailing end a² of the short cleat a below, instead engages the cleat b. Since the leading end b¹ of the cleat b is against the end guide 37 and has not moved into the notch 43, this would produce a jam or other malfunction of the dispensing apparatus which would interrupt operation and perhaps damage the apparatus.

Certain conditions of the cleat faces, particularly when the top and bottom surfaces are roughly sawed, tend to cause difficulty in the proper advancement of long cleat b just previous to its egress from the hopper, due to its interlocking with cleat c. The interlocked cleats either prevent trailing end b² of long cleat b from sliding off inclined shelf 36 and the forward end b' from entering offset 43 or caused a delayed movement of cleats adjacent the bottom of the hopper, resulting in a jam within the hopper.

Such difficulties in dispensing roughly sawed cleats of two different lengths may be eliminated by the alternate means of momentarily supporting the trailing ends of the long cleats b, as shown in Figures 7 and 8.

In Figure 7 there is shown in full lines at the left-hand side of the lower portion of hopper D a movable support 54 supporting trailing end b² of long cleat b. The upwardly extended head 55 of the movable support is pivotally mounted on a pin 57 within a slot 56 in an outwardly ex-

tending portion of a bracket 58 fastened to the lower end of wall member 8. The inner face of the bracket 58 is in alignment with the corresponding face of wall member 8, and the lower end of the bracket 58 is beveled at 61 to cooperate with a corresponding beveled face 62 of movable support 54 in limiting movement of the movable support 54 in a counter-clockwise direction, as viewed in Figure 7. Movable support 54 carries at the outer face of its L-shaped lower end (Figure 8) an elongated bar 63 (more clearly shown in Figure 7) to provide a means for operating movable support 54. To remove the movable support from the trailing end of the long cleats and to hold it normally in a clockwise position, as shown in dot-dash lines in Figure 7, there is provided a coil spring 64 compressed between the bottom of a recess 65 in the body portion of bracket 58 and a beveled surface 66 on the adjacent face of movable support 54. It will be noted that the elements 37, 41, etc. at the lower right-hand portion of the hopper of Figure 7 are the same as those previously described in connection with Figures 2 and 3.

As shown in Figures 7 and 8, the movable support 54 is operated by the spacer elements and, more specifically, by the body portions 67 of the spacer elements. Although movable support 54 is required to support the trailing ends of only the long cleats (to prevent their tipping down into the path of the push fingers of the spacer elements provided to push the short cleats) for simplicity movable support 54 is operated by each of the spacer elements as they contact elongated bar 63. It will be seen at the extreme left-hand side of Figure 7 adjacent the end of cleat support step 52, that the body portion 67 of spacer element Y (shown in broken lines) is about to contact the under surface of elongated bar 63. Continued movement of spacer element Y in the direction indicated by arrow 51 will cause movable support 54 to rotate counterclockwise, as indicated by arrow 68, against the resistance of spring 64, until the beveled face 62 of support 54 approaches or contacts stop 61 of bracket 58, as shown in full lines in Figure 7. Support 54 will remain in this position, supporting the trailing end b² of long cleat b until the body portion 67 of spacer element Y passes from beneath elongated bar 63, and allows spring 64 to move support 54 to its clockwise position out of the way of long cleat b. Since by this time push finger Y' of spacer element Y will have passed beneath the trailing end b² of long cleat b, as shown in dot-dash lines in Figure 7, any possibility that the trailing end of long cleat b may tip down into the path of push finger Y' is substantially eliminated. The action of movable support 54 in contacting the trailing end of each long cleat contributes the additional desirable effect of tending to separate cleats that are locked together, thereby allowing proper progress of the cleats in the hopper.

A solenoid or other suitable device could be used to actuate movable support 54 in timed relationship with the cleat-pushing element instead of the direct contact of body portion 67 with elongated bar 63.

In Figures 9 and 10 there is shown an apparatus for effectively separating the interlocking surfaces of roughly sawed cleats by causing oscillation of the long cleats at the lower end of the hopper relative to the adjacent short cleats, thus shearing their locked interfaces. As may

be seen in Figure 9, in lieu of the semi-fixed end guides 34 and 37 described in connection with Figure 2, oscillating members 70 are provided, their inner faces in alignment with the corresponding faces of wall members 8 and 9. The upper ends of the oscillating members 70 are pivotally mounted at 71 to brackets 72 secured to the outer faces of the wall members. At the left-hand side of hopper D, the oscillating member 70 is interposed between the bottom of a cut-away portion of wall member 8 and an inclined shelf 73 which is fastened to the upstanding angle member 10. At the right-hand side of said hopper, oscillating member 70 is interposed between the bottom of a cut-away portion of wall member 9 and exit gate support 75 fastened to upstanding angle member 10. The two oscillating members 70 are tied together by a bar 79 pivotally attached at its opposite ends to the two oscillating members by pins 78 and eyes 77 secured near the center of the outer surface of each of the oscillating members.

To communicate movement to oscillating members 70, power is derived from drive shaft 14, the end of which at the left-hand side of hopper D (Figure 9) extends outwardly beyond wall member 8 a short distance and has keyed thereto a bevel gear 80. The bevel gear 80 meshes with a similar gear 81 keyed to a short vertical shaft 83 extending through a bearing 84 supported by a bracket 85 extending from the upstanding angle member 10. To the opposite end of the shaft 83 is keyed a bevel gear 82 which meshes with a similar gear 87 keyed to one end of a short horizontal shaft 88. The shaft 88 extends through a bearing 89 supported by a bracket 90 fastened to upstanding angle member 10. Also keyed on the shaft 88 is an eccentric member 92 cooperating with a rod or follower member 93 pivotally connected to eye 77 of oscillating member 70 by pin 78.

When motor 46 (Figure 10) is energized, shaft 14 is rotated and, through the means just described, reciprocating movement is imparted to oscillating members 70, as indicated by broken lines in Figure 9. The long cleats which are within the vertical range of oscillating members 70 are thus moved longitudinally forward and backward through short distances. When either short cleat a or long cleat b moves downwardly to the point of clearing the lower end of the oscillating member 70 at the right-hand side of hopper D and has its forward end abutting fixed guide portion 94 of exit gate support 75 (as is short cleat c in Figure 9) the cleat resting thereon (long cleat d in Figure 9) will be moved longitudinally relative to it, thereby causing their contiguous surfaces, if interlocked due to extreme roughness, to be sheared apart, and allowing inclined shelf 73 to function properly with the cooperation of offset 95 in assuring the dependable supply of cleats to the conveyors.

It will thus be seen that the present invention provides apparatus for reliably dispensing cleats of at least two different lengths to a box-making machine. It should be emphasized, however, that the particular embodiments of the invention shown and described herein are intended as merely illustrative and not as restrictive of the invention.

I claim:

1. Apparatus for dispensing cleats of at least two different lengths to a box-making machine of the type having cleat pushing elements movable along a path and a cleat supporting track below said path to support cleats moved by said

elements, said apparatus comprising a cleat hopper including upstanding side and end guides for confining against lateral and longitudinal movement cleats stacked generally above and in alignment with said cleat supporting track for successive removal of said cleats from the bottom of such stack by said cleat pushing elements, the end guide at the trailing ends of the cleats in said stack having near its lower end a cleat engaging surface projecting into said hopper in position to engage the trailing ends of the longer cleats in approximately the third-from-bottom position in said stack, and the end guide at the leading ends of the cleats in said stack having its lower end positioned to engage and prevent the forward movement from said hopper of all but the bottom cleat of said stack and having near its lower end a recess to receive the leading ends of the longer cleats when said leading ends reach the second-from-bottom position in said stack and allow said cleats to be forced forwardly over said cleat engaging surface as their trailing ends move downwardly so that their trailing ends will clear said cleat engaging surface and drop into the path of said cleat pushing elements as the cleats reach the bottom of said stack.

2. Apparatus as claimed in claim 1 wherein said hopper is arranged to permit frictional engagement between the upper surface of the bottom cleat in said stack and the lower surface of the next cleat above during the time said bottom cleat is being pushed forwardly from said stack by one of said cleat pushing elements, whereby to urge said next cleat above forwardly in said hopper so that its trailing end can clear said cleat engaging surface.

3. Apparatus for dispensing cleats of at least two different lengths to a box-making machine of the type having cleat pushing elements movable along a path and a cleat supporting track below said path to support cleats moved by said elements, said apparatus comprising a cleat hopper including upstanding side and end guides for confining against lateral and longitudinal movement cleats stacked generally above and in alignment with said cleat supporting track for successive removal of said cleats from the bottom of such stack by said cleat pushing elements, the end guide at the trailing ends of the cleats in said stack having near its lower end a cleat engaging surface projecting into said hopper in position to engage the trailing ends of the longer cleats in approximately the third-from-bottom position in said stack and the end guide at the leading ends of the cleats in said stack having its lower end positioned to engage and prevent the forward movement from said hopper of all but the bottom cleat of said stack and having near its lower end a recess to receive the leading ends of the longer cleats when said leading ends reach the second-from-bottom position in said stack and allow said cleats to be forced forwardly over said cleat engaging surface as their trailing ends move downwardly so that their trailing ends will clear said cleat engaging surface and drop into the path of said cleat pushing elements as the cleats reach the bottom of said stack, a cleat guideway communicating with said hopper to permit the lateral movement of cleats from said guideway into said hopper, said guideway having at one side, in position for frictional engagement with the cleats therein, a movable cleat conveyor and means to drive said cleat conveyor at a speed tending to supply cleats to said hopper at a rate slightly in excess of the rate at which cleats are

removed from said conveyor by said cleat pushing elements, whereby to exert on the stack of cleats in the hopper a continuous pressure urging said cleats toward the bottom of said hopper.

5 4. Apparatus for dispensing cleats of at least
two different lengths to a box-making machine of
the type having cleat pushing elements movable
along a path and a cleat supporting track below
said path to support cleats moved by said ele-
10 ments, said apparatus comprising a cleat hopper
including upstanding side and end guides for
confining against lateral and longitudinal move-
ment cleats stacked generally above and in align-
15 ment with said cleat supporting track for suc-
cessive removal of said cleats from the bottom
of such stack by said cleat pushing elements, the
end guide at the trailing ends of the cleats in
said stack having near its lower end a cleat en-
18 gaging surface projecting into said hopper in po-
sition to engage the trailing ends of the longer
cleats in approximately the third-from-bottom
position in such stack and the end guide at the
leading ends of the cleats in said stack having
25 its lower end positioned to engage and prevent
the forward movement from said hopper of all
but the bottom cleat of said stack and having near
its lower end a recess to receive the leading ends
of the longer cleats when said leading ends reach
30 the second-from-bottom position in said stack
and allow said cleats to be forced forwardly over
said cleat engaging surface as their trailing ends
move downwardly so that their trailing ends will
clear said cleat engaging surface and drop into
35 the path of said cleat pushing elements as the
cleats reach the bottom of said stack, and a cleat
supporting step mounted just below the path of
said cleat pushing elements but above said cleat
supporting track to support the bottom cleat in
40 said stack.

40 5. Apparatus for dispensing cleats of at least
two different lengths to a box-making machine of
the type having cleat pushing elements movable
along a path and a cleat supporting track below
said path to support cleats moved by said ele-
45 ments, said apparatus comprising a cleat
hopper including upstanding side and end guides
for confining against lateral and longitudinal move-
ment cleats stacked generally above and in align-
50 ment with said track for successive removal
of said cleats from the bottom of such stack by
said cleat pushing elements, the end guide at
the leading ends of the cleats in said stack having
55 its lower end positioned to engage and pre-
vent forward movement from said hopper of all
but the bottom cleat in said stack, a cleat en-
gaging device movably mounted near the lower
end of the end guide at the trailing ends of the
60 cleats in such stack, and urged toward a nor-
mal position but yieldable for movement of said
cleat engaging device to an actuated position,
said cleat engaging device including a cleat en-
gaging surface arranged to project into said
65 hopper in position to engage the trailing ends
of the longer cleats in approximately the third-
from-bottom position in said stack when said
cleat engaging device is moved to its actuated
position, a push-element-engaging portion op-
eratively connected to said cleat engaging de-
70 vice and arranged to project into the path of
said cleat pushing elements at a point beyond the
line of the trailing ends of the longer cleats in
said stack when said cleat engaging device is
in normal position, whereby each of said cleat
pushing elements will engage said push-element-
75 engaging portion and move said cleat engaging

device to its actuated position at which said cleat engaging surface can engage the trailing end of a longer cleat in approximately the third-from-bottom position in said stack and prevent it from dropping into the path of said cleat pushing element until after said cleat pushing element has passed the trailing end of said longer cleat, at which time said cleat pushing element will clear said push-element-engaging portion and allow said cleat engaging device to move back to its normal position and withdraw said cleat engaging surface from engagement with the trailing end of said longer cleat, permitting the trailing end of said longer cleat to drop into the path of said cleat pushing elements in position for engagement by the next succeeding cleat pushing element.

6. Apparatus for dispensing cleats of at least two different lengths to a box-making machine of the type having cleat pushing elements movable along a path and a cleat supporting track below said path to support cleats moved by said elements, said apparatus comprising a cleat hopper including upstanding side and end guides for confining against lateral and longitudinal movement cleats stacked generally above and in alignment with said cleat supporting track for successive removal of said cleats from the bottom of said stack by said cleat pushing elements, a cleat engaging device movably mounted near the lower end of the end guide at the trailing ends of the cleats in such stack, and urged toward a normal position but yieldable for movement of said cleat engaging device to an actuated position, said cleat engaging device including a cleat engaging surface arranged to project into said hopper in position to engage the trailing ends of the longer cleats in approximately the third-from-bottom position in said stack when said cleat engaging device is moved to its actuated position, a push-element-engaging portion operatively connected to said cleat engaging device and arranged to project into the path of said cleat pushing elements when said cleat engaging device is in normal position, whereby said cleat pushing elements will engage said push element engaging portion and move said cleat engaging device to its actuated position at which said cleat engaging surface will engage the trailing ends of the longer cleats in approximately the third-from-bottom position in said stack, and the end guide at the leading ends of the cleats in said stack having its lower end positioned to engage and prevent the forward movement from said hopper of all but the bottom cleat of said stack and having near its lower end a recess to receive the leading ends of the longer cleats when said leading ends reach the second-from-bottom position in said stack and allow said cleats to be forced forwardly over said cleat engaging surface as their trailing ends move downwardly so that their trailing ends will clear said cleat engaging surface and drop into the path of said cleat pushing elements as the cleats reach the bottom of said stack.

7. Apparatus for dispensing cleats of at least two different lengths to a box-making machine of the type having cleat pushing elements movable along a path and a cleat supporting track below said path to support cleats moved by said elements, said apparatus comprising a cleat hopper including upstanding side and end guides for confining against lateral and longitudinal movement cleats stacked generally above and in alignment with said cleat supporting track for suc-

cessive removal of said cleats from the bottom of such stack by said cleat pushing elements, a cleat engaging element pivotally mounted near the lower end of the end guide at the trailing ends of the cleats in said stack, a spring biasing said cleat engaging element toward a normal position but yieldable to allow pivoting of said cleat engaging device to an actuated position, said cleat engaging element including a cleat engaging surface arranged to project into said hopper in position to engage the trailing ends of the longer cleats in approximately the third-from-bottom position in said stack when said cleat engaging element is moved to its actuated position and a push element-engaging portion operatively connected to said cleat engaging device and arranged to project into the path of said cleat pushing elements when said cleat-engaging device is in normal position, whereby said cleat pushing elements will engage said push element-engaging portion and move said cleat engaging device to its actuated position at which said cleat engaging surface will engage the trailing ends of the longer cleats in approximately the third-from-bottom position in said stack, and the end guide at the leading ends of the cleats in said stack having its lower end positioned to engage and prevent the forward movement from said hopper of all but the bottom cleat of said stack and having near its lower end a recess to receive the leading ends of the longer cleats when said leading ends reach the second-from-bottom position in said stack and allow said cleats to be forced forwardly over said cleat engaging surface as their trailing ends move downwardly so that their trailing ends will clear said cleat engaging surface and drop into the path of said cleat pushing elements as the cleats reach the bottom of said stack.

8. Apparatus for dispensing cleats of at least two different lengths to a box-making machine of the type having cleat pushing elements movable along a path and a cleat supporting track below said path to support cleats moved by said elements, said apparatus comprising a cleat hopper including upstanding side and end guides for confining against lateral and longitudinal movement cleats stacked generally above and in alignment with said cleat supporting track for successive removal of said cleats from the bottom of said stack by said cleat pushing elements, the end guide at the trailing ends of the cleats in such stack having near its lower end a cleat engaging surface projecting into said hopper in position to engage the trailing ends of the longer cleats in approximately the third-from-bottom position in such stack, and the end guide at the leading ends of the cleats in said stack having its lower end positioned to engage and prevent the forward movement from said hopper of all but the bottom cleat of said stack and having near its lower end a recess to receive the leading ends of the longer cleats when said leading ends reach the second-from-bottom position in said stack and allow said cleats to be forced forwardly by said cleat engaging surface as their trailing ends move downwardly so that their trailing ends will clear said cleat engaging surface and drop into the path of said cleat pushing elements as the cleats reach the bottom of said stack, and each of said end guides including a vertical section reciprocable longitudinally of the cleats in said stack relative to the adjacent section of said end guide, and motor means connected to drive such reciprocable sections whereby to produce longitudinal movement of the cleats within the ver-

tical range of said reciprocable sections relative to the adjacent cleats outside the vertical range of said reciprocable sections and tend to disengage any of said cleats which are interlocked due to roughness of their interfaces.

9. Apparatus for dispensing cleats of two different lengths to a box-making machine of the type having cleat pushing elements movable along a path with spaces between said cleat pushing elements for alternate longer and shorter cleats, and a cleat supporting track below said path to support cleats moved by said cleat pushing elements, said apparatus comprising a cleat hopper including upstanding side and end guides for confining against lateral and longitudinal movement, a generally vertical stack of alternately longer and shorter cleats stacked above and in alignment with said track for successive removal of said cleats from the bottom of said stack by said cleat pushing elements, the end guide at the leading ends of the cleats in said stack having its lower end positioned to engage and prevent the forward movement from said hopper of all but the bottom cleat of said stack, and the end guide at the trailing ends of the

25

cleats in such stack having near its lower end a cleat-engaging device movable between an actuated position at which it projects into said hopper in position to engage and impede downward movement of the trailing end of the long cleat in approximately the third-from-bottom position in such stack and a retracted position at which it does not engage and impede downward movement of said trailing end, and an actuator for said device operable in timed relationship with the movement of said cleat pushing elements, whereby said device will engage in succession the trailing end of each long cleat when it reaches approximately the third-from-bottom position in said stack to impede downward movement of said trailing end during the passage thereunder of a cleat pushing element for a shorter cleat, but will clear said trailing end and permit it to drop under the influence of gravity into the path of said cleat pushing elements in position for engagement by the succeeding cleat pushing elements for a longer cleat.
